UNITED STATES PATENT OFFICE.

JOSEPH LEDERER, OF NEW YORK, N. Y.

INVERTED GAS-BURNER.

No. 920,353.

Specification of Letters Patent.

Patented May 4, 1909.

Application filed July 21, 1908. Serial No. 444,575.

To all whom it may concern:

Be it known that I, JOSEPH LEDERER, a citizen of the United States, residing in the city, county, and State of New York, have 5 invented certain new and useful Improvements in Inverted Gas-Burners, of which the following is a specification.

This invention relates to inverted gas-burners of the Bunsen type and has for its 10 object the production of such an inverted gas-burner wherein a downwardly extending duct or tube supplies a proper mixture of gas and air to a plurality of arms extending from a lower part of the downward duct and provided with downwardly opening orifices for 15 the exit and ignition of the gas and air mixture and formation, upon ignition, of inverted flames adapted to render incandescent mantles for incandescent gas-light, and 20 wherein there are other features and advantages hereinafter described and claimed.

Heretofore, in the construction of inverted gas-burners of the Bunsen type for use with mantles for incandescent gas-light, difficulty 25 has been experienced, and in constructing such burners, to supply, in a single lamp, a gas and air mixture to more than one downwardly opening orifice or inverted flame and to heat to incandescence two or more inverted 30 mantles, separate downwardly extending ducts, one for each mantle and each provided with holes or openings for the admission of air, have generally been employed. The construction of such or similar gas-burners 35 for use with two or more inverted mantles is complicated, difficult, expensive and unsatisfactory.

It is the object of this invention to avoid the disadvantages referred to and to secure 40 the simplicity of construction, efficiency of operation, and other advantages herein described.

The invention is illustrated in the accompanying drawings which form part of this 45 specification.

Figure 1 is an elevation, mostly in vertical section, of an inverted gas-burner made in accordance with this invention. Fig. 2 is a plan view from above of a horizontal section 50 made along the line *a b* of Fig. 1. Fig. 3 is a plan view from above of a horizontal section made along the line *c d* of Fig. 1. Fig. 4 is an enlarged plan view from above, partly in horizontal section, of the gas-supply regula- 55 tor and air-supply ducts shown in Fig. 1. Fig. 5 is an enlarged elevation, mostly in

vertical section, of the gas-supply regulator, gas-check and air-supply ducts shown in Fig. 1.

In the drawings like letters denote like 60 parts.

A is a downwardly extending duct or tube which may consist of one part, but which is, preferably, made of several parts, as shown in the drawings. 65

B is a stop-cock for turning the gas on and off.

C is a duct for a pilot light leading from duct A above the stop-cock B.

D D are air-supply ducts, extending, preferably, horizontally and from a part E with which the duct A is provided. The ducts 70

D D, as shown, supply air to the downward duct A, preferably at a point above the point or points at which the plurality of arms F F 75 extend from a lower part of duct A. The arms F F are provided with downwardly opening orifices G G for the exit and ignition of the gas and air mixture and formation, upon ignition, of inverted flames, and the 80 orifices G G are, preferably, provided with mouth-pieces H H made of suitable, refractory material, such as porcelain or clay, having projecting points or ledges I adapted to receive and carry rings K or other suitable 85 means for attachment of one end of the inverted mantles L L.

M is a hollow piece of suitable material, such as sheet metal, preferably in the shape of a frustum of a cone, forming a conveyer of 90 the products of combustion, surrounding duct A, and supported by ducts D D which pass through it. The conveyer M extends upwardly from a line, preferably, just above inverted mantles L L. The products of combustion resulting from the inverted flames rise and pass off through the conveyer or hollow piece M and some suitable exit, such as N, with which the conveyer or an extension thereof is provided, at the upper part 95 of the inverted gas-burner. Inasmuch as the conveyer M does not extend down so as to surround the inverted mantles L L, it does not interfere with the supply of air to the mantles from the outside of the mantles. 100

As shown in Fig. 1, the upper part of the burner may be provided with a suitable casing O adapted at its lower end to support a globe P, which globe may, as shown, be closed at the bottom. The casing O or globe 110 P, with which it is provided, has holes Q through which air is drawn and supplied to

the outsides of the mantles, the products of combustion rising and passing off above through the conveyer.

R is a gas-supply regulator, shown as consisting of an accessible head on the outside of the burner and a rod, passing, preferably, horizontally through perforations of casing O, conveyer M and duct A. The perforation of duct A may be provided with screw-threads and so may the inner end of the rod, and by reason of the screw-threads, when the rod is turned, the inner end of the rod, which tapers to a point, is made to advance into or to withdraw partially from the channel of duct A.

As shown more clearly in Figs. 4 and 5, the channel of duct A is provided with a gas-check S at the place where the rod of the gas-supply regulator R enters. The gas-check 20 may consist of a piece provided with a groove or socket T inclined toward the rod of the gas-supply regulator R and with a needle U adapted to enter and close, or partially close, the contracted part V of the channel of duct 25 A. A spring W tends to raise the needle U of the gas-check above the contracted part V of the channel of duct A, but upon turning the gas-supply regulator R so as to cause the tapered end of its rod to advance into the 30 channel of duct A, the tapered end of the rod enters the inclined groove T and, as the rod advances, the needle is forced, against the action of the spring, toward or into the contracted part V of the channel of duct A. On 35 turning the gas-supply regulator R in the opposite direction, so as to withdraw its tapered end from the inclined groove T, the spring W presses the needle U upward and away from or out of the contracted part of 40 the channel of duct A. In this manner, as is well understood, the supply of gas to the burner may be regulated as desired.

The operation of an inverted gas-burner made in accordance with this invention is as follows:—On turning the stop-cock B gas enters the downwardly extending duct A and passes to the gas-check S where the supply of gas is regulated as described. Upon passing through the contracted part V of the 50 channel of duct A the gas mixes with pure air drawn from the outside of the burner through the air-ducts D D. The gas and air mixture then descends through duct A until it reaches the lower part thereof, where it is 55 supplied to the plurality of arms F F, extending therefrom, and issues from the downwardly opening orifices G G of the arms F F, where it is ignited and forms inverted flames, which heat to incandescence the inverted 60 mantles L L. The products of combustion rise and escape through the conveyer M and pass off through an opening, such as N, in the burner above the air-ducts D D. Since the 65 products of combustion pass off above the air-ducts D D and since the air-ducts D D

extend from the channel of duct A to the outside of the casing O of the burner, the supply of air through the ducts D D is a supply of pure air, not exhausted of its oxygen as are the products of combustion, and a proper 70 gas and air mixture is thus obtained for the formation of efficient, inverted Bunsen flames. For like reasons, as will be well understood, the supply of air to the outside of the mantles through openings such as Q, is a 75 similarly pure supply of air.

In an inverted gas-burner constructed in accordance with this invention the supply of gas can be regulated conveniently, because the gas-supply regulator R extends to the 80 outside of the casing O and is located below the point at which the products of combustion escape from the burner, so that it is accessible for manipulation and does not become highly heated. A proper supply of 85 pure air to the burner is obtained through the air-ducts D D which supply air to the downwardly extending duct A and a plurality of efficient inverted Bunsen flames is obtained at the orifices of the plurality of arms 90 extending from a lower part of the downwardly extending duct A. By this simple arrangement of parts, in accordance with this invention, there is obtained, in a single gas-burner, a plurality of efficient, inverted Bunsen 95 flames adapted to heat to incandescence a plurality of inverted mantles without the complicated construction, expense or disadvantages heretofore experienced in the construction of burners to produce in a single 100 gas-lamp a number of inverted flames.

What I claim is:—

1. In a gas-burner for use with mantles for incandescent gas-light, the combination of a downwardly extending duct for gas and air, which is provided with an inlet for air, a plurality of arms extending from a lower part of the downward duct and provided with downwardly opening orifices for the exit and ignition of the gas and air mixture and formation, upon ignition, of inverted flames, 105 and a conveyer of the products of combustion extending upwardly above said orifices beyond the inlet for air, substantially as 110 described.

2. In a gas-burner for use with mantles for incandescent gas-light, the combination of a downwardly extending duct for gas and air extending to the lower part of said burner, a duct for air communicating with 115 the downward duct, and a plurality of arms extending laterally from a lower part of the downward duct and provided with downwardly opening orifices for the exit and ignition of the gas and air mixture and formation, upon ignition, of inverted flames, substantially as described.

3. In a gas-burner for use with mantles for incandescent gas-light, the combination of a downwardly extending duct for gas and 120

- air extending to the lower part of said burner, a plurality of ducts for air communicating with the downward duct, and a plurality of arms extending laterally from a lower part of the downward duct and provided with downwardly opening orifices for the exit and ignition of the gas and air mixture and formation, upon ignition, of inverted flames, substantially as described.
4. In a gas-burner for use with mantles for incandescent gas-light, the combination of a downwardly extending duct for gas and air extending to the lower part of said burner, provided with an inlet for air and with a gas-check above the inlet for air, and a plurality of arms extending laterally from a lower part of the downward duct and provided with downwardly opening orifices for the exit and ignition of the gas and air mixture and formation, upon ignition, of inverted flames, substantially as described.
5. In a gas-burner for use with mantles for incandescent gas-light, the combination of a downwardly extending duct for gas and air extending to the lower part of said burner, a duct for air communicating with the downward duct, a gas-check above the air duct, and a plurality of arms extending laterally from a lower part of the downward duct and provided with downwardly opening orifices for the exit and ignition of the gas and air mixture and formation, upon ignition, of inverted flames, substantially as described.
6. In a gas-burner for use with mantles for incandescent gas-light, the combination of a downwardly extending duct for gas and air extending to the lower part of said burner, a plurality of air-ducts communicating with the downward duct, a gas-check above the air-ducts, and a plurality of arms extending laterally from a lower part of the downward duct and provided with downwardly opening orifices for the exit and ignition of the gas and air mixture and formation, upon ignition, of inverted flames, substantially as described.
7. In a gas-burner for use with mantles for incandescent gas-light, the combination of a downwardly extending duct for gas and air, a conveyer surrounding the downward duct, a duct for air passing through the conveyer and communicating with the downward duct, and a plurality of arms extending from a lower part of the downward duct and provided with downwardly opening orifices for the exit and ignition of the gas and air mixture and formation, upon ignition, of inverted flames, substantially as described.
8. In a gas-burner for use with mantles for incandescent gas-light, the combination of a downwardly extending duct for gas and air, a conveyer surrounding the downward duct, a plurality of ducts for air passing through the conveyer and communicating with the down-
- ward duct, and a plurality of arms extending from a lower part of the downward duct and provided with downwardly opening orifices for the exit and ignition of the gas and air mixture and formation, upon ignition, of inverted flames, substantially as described.
9. In a gas-burner for use with mantles for incandescent gas-light, the combination of a downwardly extending duct for gas and air, a conveyer surrounding the downward duct, a casing provided with a globe and air-inlet holes, a duct for air passing through the casing and conveyer and communicating with the downward duct, and a plurality of arms extending from a lower part of the downward duct and provided with downwardly opening orifices for the exit and ignition of the gas and air mixture and formation, upon ignition, of inverted flames, substantially as described.
10. In a gas-burner for use with mantles for incandescent gas-light, the combination of a downwardly extending duct for gas and air, a conveyer surrounding the downward duct, a casing provided with a globe and air-inlet holes, a plurality of ducts for air passing through the casing and conveyer and communicating with the downward duct, and a plurality of arms extending from a lower part of the downward duct and provided with downwardly opening orifices for the exit and ignition of the gas and air mixture and formation, upon ignition, of inverted flames, substantially as described.
11. In a gas-burner for use with mantles for incandescent gas-light, the combination of a downwardly extending duct for gas and air, a conveyer surrounding the downward duct, a casing provided with a globe and air-inlet holes, a duct for air passing through the casing and conveyer and communicating with the downward duct, and a plurality of arms extending from a lower part of the downward duct and provided with downwardly opening orifices for the exit and ignition of the gas and air mixture and formation, upon ignition, of inverted flames, the conveyer extending upward above the orifices, substantially as described.
12. In a gas-burner for use with mantles for incandescent gas-light, the combination of a downwardly extending duct for gas and air, a conveyer surrounding the downward duct, a casing provided with a globe and air-inlet holes, a plurality of ducts for air passing through the casing and conveyer and communicating with the downward duct, and a plurality of arms extending from a lower part of the downward duct and provided with downwardly opening orifices for the exit and ignition of the gas and air mixture and formation, upon ignition, of inverted flames, the conveyer extending upward above the orifices, substantially as described.
13. In a gas-burner for use with mantles for incandescent gas-light, the combination

of a downwardly extending duct for gas and air, a conveyer surrounding the downward duct, a duct for air passing through the conveyer and communicating with the downward duct, and a plurality of arms extending from a lower part of the downward duct and provided with downwardly opening orifices for the exit and ignition of the gas and air mixture and formation, upon ignition, of inverted flames, the conveyer being provided with an outlet for the products of combustion above the duct for air, substantially as described.

14. In a gas-burner for use with mantles for incandescent gas-light, the combination of a downwardly extending duct for gas and air, a conveyer surrounding the downward duct, a plurality of ducts for air passing through the conveyer and communicating with the downward duct, and a plurality of arms extending from a lower part of the downward duct and provided with downwardly opening orifices for the exit and ignition of the gas and air mixture and formation, upon ignition, of inverted flames, the conveyer being provided with an outlet for the products of combustion above the ducts for air, substantially as described.

15. In a gas-burner for use with mantles for incandescent gas-light, the combination of a downwardly extending duct for gas and air, a conveyer surrounding the downward duct, a duct for air passing through the conveyer and communicating with the downward duct, a gas-supply regulator extending from the outside of the conveyer to the downward duct, and a plurality of arms extending from a lower part of the downward duct and provided with downwardly opening orifices for the exit and ignition of the gas and air mixture and formation, upon ignition, of inverted flames, substantially as described.

16. In a gas-burner for use with mantles for incandescent gas-light, the combination of a downwardly extending duct for gas and air provided with a downwardly opening ori-

fice for the exit and ignition of the gas and air mixture and formation, upon ignition, of an inverted flame, a conveyer surrounding the downward duct, a duct for air passing through the conveyer and communicating with the downward duct, and a gas-supply regulator extending from the outside of the conveyer to the downward duct, substantially as described.

17. In a gas-burner for use with mantles for incandescent gas-light, the combination of a downwardly extending duct for gas and air, a conveyer surrounding the downward duct, a duct for air passing through the conveyer and communicating with the downward duct, a gas-supply regulator extending from the outside of the conveyer to the downward duct, and a plurality of arms extending from a lower part of the downward duct and provided with downwardly opening orifices for the exit and ignition of the gas and air mixture and formation, upon ignition, of inverted flames, the conveyer being provided with an outlet for the products of combustion above the gas-supply regulator, substantially as described.

18. In a gas-burner for use with mantles for incandescent gas-light, the combination of a downwardly extending duct for gas and air provided with a downwardly opening orifice for the exit and ignition of the gas and air mixture and formation, upon ignition, of an inverted flame, a conveyer surrounding the downward duct, a duct for air passing through the conveyer and communicating with the downward duct, and a gas-supply regulator extending from the outside of the conveyer to the downward duct, the conveyer being provided with an outlet for the products of combustion above the gas-supply regulator.

JOSEPH LEDERER.
